CENTRIFUGAL PENDULUM

Louis Birkigt, Versoix, near Geneva, Switzerland,
assignor to Gilles Francois Sarazin, Saint-Prix
(Seine-et-Oise), France

Application November 17, 1943, Serial No. 510,704
In France April 7, 1943

22 Claims. (Cl. 74—574)

The present invention relates to centrifugal pendulums, and is more especially, although not exclusively concerned, among these apparatus, with those for use in dynamic vibration dampers. This expression "dynamic vibration damper" must be understood to include any device in which at least one centrifugal pendulum is brought into action by the occurring of a vibration and tends, through its reactions on the rotating part upon which it is mounted, to oppose the perturbing displacements which would otherwise be imparted to said rotating part as a result of this vibration.

It has already been proposed to make centrifugal pendulums in the form of bifilar pendulums, in order to avoid their oscillation producing a rotation of the pendular mass about its center of gravity, and to have their frequency independent of the magnitude of said mass.

In the French Patents No. 724,234 and No. 783,734 and the French addition Patent No. 41,251 various solutions have been described for the suspension of the pendular mass, through links either real or fictitious.

The object of the present invention is to provide a centrifugal pendulum of the type above stated which is suspended in a manner better adapted to meet the requirements of practice than it was the case with the prior apparatus.

With this object in view, according to a first feature of the present invention, the means for the suspension of the pendular mass of bifilar centrifugal pendulums consist of flexible links fixed, on the one hand, to the mass, and, on the other hand, to the rotating part upon which the pendulum is mounted, these links winding and unwinding, at their ends, during the pendular oscillation, on convex supporting surfaces respectively rigid with the pendular mass and with the rotating part.

According to another feature of the invention, which is applicable to all centrifugal pendulums, whatever be their kind of suspension, the means for suspending the pendular mass are arranged in such manner that a given increase of the centrifugal force due to the rotation of the rotating part upon which the pendulum is mounted produces an increase of the length of the theoretical pendulum equivalent to the centrifugal pendulum that is being considered.

Other features of the present invention will result from the following detailed description of some specific embodiments thereof.

Preferred embodiments of the present invention will be hereinafter described, with reference to the accompanying drawings, given merely by way of example, and in which:

Fig. 1 is a diagrammatical view in elevation of a centrifugal pendulum made according to the invention;

Fig. 2 is a sectional view on the line II—II of Fig. 1;

Fig. 3 is a sectional view on a larger scale of a centrifugal pendulum made according to one embodiment of the invention;

Fig. 4 is a view, corresponding to Fig. 3, partly in sectional view on the line IV—IV of Fig. 3 and partly in elevational view;

Fig. 5 shows another embodiment of the invention, being a sectional view on the line V—V of Fig. 6;

Fig. 6 is a sectional view on the line VI—VI of Fig. 5;

Fig. 7 is a perspective view of the centrifugal pendulum of Figs. 5 and 6;

Fig. 8 is a perspective view of some elements of this pendulum prior to their assembly;

Fig. 9 is a diagrammatical view of a pendulum made, according to the invention, in such manner that its pendular length can increase in accordance with the centrifugal force.

In the following description, it will be supposed that it is desired to provide a bifilar centrifugal pendulum intended for instance for a torsional vibration damper for a driving shaft 1.

This shaft 1 is provided with a plate or disc 2 and this disc is connected to a pendular mass 3 through at least two flexible links 4, each of which is applied at its ends on convex surfaces 5 and 6 belonging respectively to mass 3 and disc 2.

These surfaces 5 and 6 are arranged in such manner that the links 4 remain always tangent thereto during the whole of the pendular oscillation, the maximum amplitude of which is $2A$.

Preferably, these surfaces are given the shape of equal surfaces of revolution about axes B and C, respectively fixed with respect to the pendular mass and to the disc carried by shaft 1.

According to the invention, which is diagrammatically illustrated by Figs. 1 and 2, axes B and C are common to the surfaces that cooperate with the right and left flexible links of the bifilar suspension. The surfaces 5 that belong to the pendular mass may then be given the shape of a complete surface of revolution, and the surfaces 6 that belong to disc 2 are given an identical shape.

In this case links 4 can consist of loops passing around said surfaces, in a manner analogous to that of a belt passing around two pulleys of equal diameters.

It will be readily understood that, with such an arrangement, when mass 3 is given a pendular oscillatory movement, it remains constantly parallel to itself. In other words, the movement it undergoes is of the translatory kind.

Links 4 can be constituted by wires or thin bands, for instance of textile material (natural or artificial silk), or of metal either in the form of wires or of steel or other metal ribbons of a

thickness averaging one tenth of a millimeter. Each link may be constituted by one or several flexible bands, for instance two wires in the case illustrated by Figs. 1 and 2.

The pendular length r' will be, in this case, equal to the distance between axes B and C. It will be chosen in accordance with the natural period that the pendulum to obtain is to have for each revolution of shaft 1.

Of course, links 4, instead of being in the form of complete loops, may be made each in the form of separate elements. The ends of these elements will then be fixed respectively to surfaces 5 and 6 at points thereof such that, when the pendulum oscillates with the maximum amplitude 2A, said link elements still remain tangentially applied against said surfaces.

I might also limit each of the surfaces in question to the arcs, corresponding to an angle 2A, along which, during the oscillation, moves the point of tangential contact of the link element with said surfaces.

I might also provide, for each link, centers B₁, C₁ and B₂, C₂ such that B₁ and B₂ on the one hand and C₁ and C₂ on the other hand do not coincide. In this case the distance from B₁ to B₂ must be equal to the distance from C₁ to C₂. Likewise, the distances from B₁ to C₁ and from B₂ to C₂ must be equal to each other and to the pendular length r' .

A device embodying these conditions is illustrated by Figs. 3 and 4.

If, as it is the case in the arrangement shown by these figures, length r' is smaller than the height of the arcs of surfaces 5 and 6 along which move the points of tangential contact of links 4 therewith, these surfaces 5 and 6 are advantageously made as follows, as illustrated by said Figs. 3 and 4: They are given a comb-like structure, that is to say are provided with teeth extending along the directrices of said surfaces and engaging between one another with a certain play. For instance, a tooth or element 7 of one of the surfaces, say 5, passes freely between two teeth or elements 8 of the other surface 6. In this case, the links will be given the shape of bands simultaneously in contact with portions of said teeth 7 and 8. Thus the pendular length r' can be made as small as it is desired with reference to the common radius of surfaces 5 and 6.

The fixation of bands 4 respectively to the pendular mass 3 and the disc 2 carried by the shaft may, for instance, be obtained, as shown by Fig. 3, by means of screws such as 9 and 10 arranged to hold the ends of said bands 4 tightly against portions of surfaces 5 and 6.

According to the embodiment illustrated by Figs. 5 to 8, the pendular mass is constituted by the superposition of three plates, which may for instance be obtained by merely cutting them by means of a press from steel plates. The two outer plates or discs, 19 and 20, are made of the same thickness, a_1 , while the inner plate or disc 21 is made of a thickness b_1 substantially equal to two of a_1 . These three plates are suitably fixed together, for instance by means of rivets.

These plates or discs are given the general shape of semi-circles. But each of the outer plates 19 and 20 is provided with projections at the respective ends of the diameter by which it is limited, these projections of the cylindrical periphery of the plate constituting the equivalent of the teeth 8 of the embodiment of Figs. 3 and 4. On the contrary, the inner plate 21 is bevelled at the ends of the diameter to which it is limited.

Of course, this arrangement might be reversed, that is to say the outer plates 19 and 20 might be bevelled, while the inner plate 21 would be provided with projections such as 8.

The support to be fixed to the disc 2 carried by shaft 1 for cooperating with the pendular mass thus formed is also made by the superposition of three plates similar to those above referred to, but which are preferably given slightly different thicknesses. For instance, if the teeth 8 are carried by the outer plates 19 and 20 of the pendular mass, the outer plates 22 and 23 of the support will be made of a thickness a_2 greater than a_1 by some tenths of a millimeter, while the inner plate 24 of said support will be given a thickness b_2 smaller than b_1 by some tenths of a millimeter.

In the embodiment illustrated by the drawings, in which the inner plate 21 of the pendular mass is bevelled at the ends of the diameter by which it is limited, the inner plate 24 of the support is provided, at the ends of the diameter by which it is limited, with projections constituting the equivalent of teeth 7 of the embodiment of Figs. 3 and 4. On the contrary, the ends of the diameter edges of plates 22 and 23 are bevelled so as to correspond to the projections 8 of the plates 19 and 20 of the pendular mass. Thus, opposite each tooth 7 or 8 there is provided a hollow space of corresponding width and shape, whereby, once the links 4 have been fixed in position, for instance by fixation to the middle plates 21 and 24, the pendular movement can take place freely.

The support constituted by the superposition of plates 22, 23 and 24 can be fixed through any suitable means to disc 2, for instance by means of the rivets 25 through which the plates in question are assembled together.

Whatever be the particular embodiment that is chosen, I obtain, according to the present invention, a bifilar centrifugal pendulum which is particularly simple and economic to manufacture. This pendulum is also very strong, owing to the fact that links 4, which are well guided by surfaces 5 and 6, are not subjected to important flections capable of breaking them.

A centrifugal pendulum made as above described may also involve the following feature, which may, in some cases, be used separately.

According to this feature, the suspension means of the pendular mass of the apparatus is arranged in such manner that a given increase of the centrifugal force due to the rotation of shaft 1 produces an increase of the pendular length r' of the pendulum.

For this purpose, in a construction of the type above described for the obtainment of a bifilar pendulum, I provide each of the links 4 with an elastic system such that these links are given a certain increase of length under the effect of a given increase of the centrifugal force.

For instance, in order to obtain this result, instead of fixing these links in a rigid manner at both of their ends, they are elastically mounted at least at one of their ends, for instance that which is secured to disc 2.

An embodiment of such a device is shown by Fig. 9.

In this construction, one end, that located on the side of disc 2, of each of the links 4 is fixed to an arm 11 capable of pivoting about axis C through an angle D corresponding to an arc of the surface 6 which coacts with the link 4 that is being considered, said arc corresponding to angle D being located beyond the arc corresponding to the maximum amplitude 2A.

In order to urge this arm 11 in the direction tending to shorten the length of the corresponding link 4, there is provided a spring 12 of determined strength, whereby arm 11 assumes constantly the desired position under the opposed effects of spring 12 and the pull exerted by the centrifugal force on link 4.

Advantageously, I synchronize the displacements of the two arms 11 corresponding to the same pendulum, whereby both of the links thereof are always of the same length. This result is for instance obtained, as shown by Fig. 9, by means of two rods 13 pivoted to each other about a pin slideable in a symmetrically disposed slot.

Instead of leaving the system thus provided free to work in such manner that, to every value of the centrifugal force, there corresponds a well determined pendular length r' , it may be advantageous to provide means such that, when the centrifugal force gradually increases, the pendular length successively passes through given values r'_1, r'_2, r'_3 and stays at each of these values for a predetermined zone of variation of the centrifugal force.

With this object in view, for instance, I fix on the spindle of lever 11 a disc 14 the periphery of which is provided with suitably located notches 15, while a resiliently locking member 16 pushed by a spring 17, is adapted to engage into that of said notches which is passing opposite it.

It will be readily understood that if member 16 is, for instance, engaged in the first of these notches 15 (position shown by Fig. 9), it remains therein as long as the centrifugal force has not reached a value capable of driving member 16 out from said notch by causing it to slide along the inclined edge thereof. When the centrifugal force exceeds this value, disc 14 and lever 11 are suddenly caused to pass to the next position, for which member 16 engages the second notch 15, and so on.

By suitably arranging and adjusting the device, it is possible, for instance, to obtain a variation of r' such that there is obtained, for each whole zone of speeds of revolution as hereinafter set forth, the pendular order indicated opposite the mean value of said zone:

Speed N_1 (say 2000 revs. p. m.)—order n_1 (say 3);
Speed N_2 (say 2400 revs. p. m.)—order n_2 (say 2.5);

Speed N_3 (say 3000 revs. p. m.)—order n_3 (say 2).

If necessary, and in order to render the adjustment system more sensitive, means may be provided for reducing the friction resulting from the displacement that takes place between links 4 and the surfaces along which said links wind and unwind, when the pendular length varies and said surfaces are fixed.

For this purpose, for instance, I may provide rollers 18 or the like between each link 4 and the surface which supports it. Alternately, I might arrange said surfaces in such manner as to have them pivoting as a whole about axis C when lever 11 itself pivots.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the appended claims.

What I claim is:

1. In combination with rotating means, a dynamic vibration damping device including a pendulum which comprises in combination, a supporting part, a pendular mass, at least two corresponding surfaces, one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation.
2. In combination with rotating means, a dynamic vibration damping device including a pendulum which comprises, in combination, a supporting part, a pendular mass, two pairs of corresponding surfaces, each pair consisting of a surface rigid with said supporting part and an equal surface rigid with said pendular mass, these two last mentioned surfaces being of revolution about respective axes fixed to said supporting part and to said mass, respectively, and two flexible links each secured at one end to said supporting part and at the other end to said pendular mass so as each to pass around the two surfaces of one pair and to wind on one of said two surfaces while simultaneously unwinding from the other during pendular oscillation.
3. In combination with rotating means, a dynamic vibration damping device including a pendulum which comprises, in combination, a supporting part, a pendular mass, two pairs of corresponding surfaces, each pair consisting of a surface rigid with said supporting part and a corresponding surface rigid with said pendular mass, the surfaces rigid with the supporting part being elements of a surface of revolution about an axis fixed with respect to said part, and the surfaces rigid with the pendular mass being equal elements of a surface of revolution about an axis fixed with respect to said mass, and two flexible links each secured at one end to said supporting part and at the other end to said pendular mass so as each to pass around the two surfaces of one pair and to wind on one of said two surfaces while simultaneously unwinding from the other during pendular oscillation.
4. In combination with rotating means, a dynamic vibration damping device including a pendulum which comprises, in combination, a supporting part, a pendular mass, two identical surfaces of revolution one rigid with said supporting part and the other rigid with said pendular mass, and flexible means connecting said supporting part and said pendular mass in spaced relationship and disposed so as to pass around the two surfaces and to wind on one while simultaneously unwinding from the other during pendular oscillation.
5. In combination with rotating means, a dynamic vibration damping device including a pendulum which comprises, in combination, a supporting part, a pendular mass, at least two corresponding surfaces, one rigid with said supporting part and the other rigid with said pendular mass, and two flexible elements each secured at one end to said supporting part and at the other end to said pendular mass so as each to pass around the two surfaces and to wind on one while simultaneously unwinding from the other during pendular oscillation.
6. In combination with rotating means, a dynamic vibration damping device including a pendulum which comprises, in combination, a supporting part, a pendular mass, at least

two corresponding surfaces, one rigid with said supporting part and the other rigid with said pendular mass, and two flexible bands each secured at one end to said supporting part and at the other end to said pendular mass so as each to pass around the two surfaces and to wind on one while simultaneously unwinding from the other during pendular oscillation.

7. In combination with rotating means, a dynamic vibration damping device including a pendulum which comprises, in combination, a supporting part, a pendular mass, at least two corresponding surfaces one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation, said links being respectively secured to said surfaces at points such that, for the maximum amplitude of oscillation, the links remain tangent to said surfaces.

8. In combination with rotating means, a dynamic vibration damping device including a pendulum which comprises, in combination, a supporting part, a pendular mass, two pairs of corresponding surfaces, each pair consisting of a surface rigid with said supporting part and a corresponding surface rigid with said pendular mass, and two flexible links each secured at one end to said supporting part and at the other end to said pendular mass so as each to pass around the two surfaces of one pair and to wind on one of said surfaces while simultaneously unwinding from the other during pendular oscillation, each surface being limited to the portion along which moves the point of tangency of the corresponding link thereon, for the maximum amplitude of oscillation.

9. In combination with rotating means, a dynamic vibration damping device including a pendulum which comprises, in combination, a supporting part, a pendular mass, two pairs of corresponding surfaces, each pair consisting of a surface rigid with said supporting part and an equal surface rigid with said pendular mass, these two last mentioned surfaces being of revolution about respective axes fixed to said supporting part and to said mass, respectively, the distance between the axes of the surfaces rigid with the supporting part being equal to the distance between the axes of the surfaces rigid with the pendular mass, and two flexible links each secured at one end to said supporting part and at the other end to said pendular mass so as each to pass around the two surfaces of one pair and to wind on one of said two surfaces while simultaneously unwinding from the other during pendular oscillation.

10. In combination with rotating means, a dynamic vibration damping device including a pendulum which comprises, in combination, a supporting part, a pendular mass, two pairs of corresponding surfaces, each pair consisting of a surface rigid with said supporting part and a corresponding surface rigid with said pendular mass, and two flexible links each secured at one end to said supporting part and at the other end to said pendular mass so as each to pass around the two surfaces of one pair and to wind on one of said surfaces while simultaneously unwinding from the other during pendular oscillation, said surfaces being of comb-like structure, so that the

teeth of one of them engage freely between the teeth of the corresponding one.

11. In combination with rotating means, a dynamic vibration damping device including a pendulum which comprises, in combination, a supporting part constituted by a plate the edge of which is of circular shape, extending over more than one semi-circle, a pendular mass constituted by a plate parallel to the first mentioned plate and the edge of which is of circular shape, extending over more than one semi-circle of the same diameter as the first mentioned one, and two flexible bands each secured at one end to the circular edge of one of said plates and at the other end to the circular edge of the other plate so that each band is tangent to the edges of the two plates in such manner as to wind on one of said edges while simultaneously unwinding from the other during pendular oscillation.

12. In combination with rotating means, a dynamic vibration damping device including a pendulum which comprises, in combination, a part formed by three semi-circular discs assembled together side by side, the two outer discs including projections beyond the diameters that limit them so that their peripheries cover more than one semi-circle and the inner disc being bevelled at its ends so that its periphery covers less than one semi-circle, another part made of three semi-circular discs of the same diameter as the first mentioned discs assembled together side by side, the two outer discs being bevelled and the inner one provided with projections, one of said composite parts forming the supporting part of the pendulum and the other the pendular mass, and at least one flexible band each secured both to the circular edge of one of said parts and to the circular edge of the other part, so as to wind on one of said edges while unwinding from the other during the pendular movement, the thicknesses of said discs being so chosen that the projections of one disc can move freely in the spaces corresponding to the bevelled portions of the corresponding disc of the other part.

13. In combination with rotating means, a dynamic vibration damping device including a pendulum which comprises, in combination, a part formed by three semi-circular discs assembled together side by side, the two outer discs including projections beyond the diameters that limit them so that their peripheries cover more than one semi-circle and the inner disc being bevelled at its ends so that its periphery covers less than one semi-circle, another part made of three semi-circular discs of the same diameter as the first mentioned discs assembled together side by side, the two outer discs being bevelled and the inner one provided with projections, one of said composite parts forming the supporting part of the pendulum and the other the pendular mass, and two flexible bands each secured at one end to the circular edge of one of said parts and at the other end to the circular edge of the other part, so as to wind on one of said edges while unwinding from the other during the pendular movement, the thicknesses of said discs being so chosen that the projections of one disc can move freely in the spaces corresponding to the bevelled portions of the corresponding disc of the other part.

14. In combination with rotating means, a dynamic vibration damping device including a pendulum which comprises, in combination, a part formed by three semi-circular discs assembled together side by side, the two outer

discs including projections beyond the diameters that limit them so that their peripheries cover more than one semi-circle and the inner disc being bevelled at its ends so that its periphery covers less than one semi-circle, another part made of three semi-circular discs of the same diameter as the first mentioned discs assembled together side by side, the two outer discs being bevelled and the inner one provided with projections, one of said composite parts forming the supporting part of the pendulum and the other the pendular mass, and two flexible bands each secured at one end to the circular edge of one of said parts and at the other end to the circular edge of the other part, so as to wind on one of said edges while unwinding from the other during the pendular movement, the thickness of each of the outer discs of the first mentioned composite part being smaller than that of the corresponding disc of the other part, while the thickness of the inner disc of the first mentioned part is greater than that of the inner disc of the other part, whereby the projections of one disc can move freely in the spaces corresponding to the bevelled portions of the corresponding disc of the other part.

15. In combination with rotating means, a dynamic vibration damping device including a pendulum which comprises, in combination, a supporting part, a pendular mass, at least two corresponding surfaces, one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation, said links being adapted to produce increase of the pendular radius when the centrifugal force increases.

16. In combination with rotating means, a dynamic vibration damping device including a pendulum which comprises, in combination, a supporting part, a pendular mass, at least two corresponding surfaces one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation, said links being elastically secured to at least one of the two parts to which they are secured at their ends so as to produce an increase of the pendular radius in response to an increase of the centrifugal force.

17. In combination with rotating means, a dynamic vibration damping device including a pendulum which comprises, in combination, a supporting part, a pendular mass, at least two corresponding surfaces, one of circular shape rigid with said supporting part and the other with said pendular mass, and two flexible links each secured at one end elastically to said supporting part and at the other end rigidly to said pendular mass so as to pass around said two surfaces and to wind around one while simultaneously unwinding from the other during pendular oscillation, the elastic securing of at least one link to said supporting part consisting of an arm pivoted about the center of the circular-shaped surface of said supporting part, with means for fixing the end of said link to the end of said arm,

and elastic means for yieldingly opposing the rotation of said arm under the action of the centrifugal force.

18. In combination with a rotating means, a dynamic vibration damping device according to claim 15, in which said pendulum includes means for limiting the increase in the pendular radius to stages each dependent upon the reaching of predetermined amounts of centrifugal force of said pendular mass.

19. In combination with rotating means, a dynamic vibration damping device including a pendulum which comprises, in combination, a supporting part, a pendular mass, at least two corresponding surfaces, one of circular shape rigid with said supporting part and the other with said pendular mass, and two flexible links each secured at one end elastically to said supporting part and at the other end rigidly to said pendular mass so as to pass around said two surfaces and to wind around one while simultaneously unwinding from the other during pendular oscillation, the elastic securing of at least one link to said supporting part consisting of an arm pivoted about the center of the circular-shaped surface of said supporting part, with means for fixing the end of said link to the end of said arm, elastic means for yieldingly opposing the rotation of said arm under the action of the centrifugal force, and means for resiliently locking the rotation of said arm in predetermined angular positions thereof.

20. In combination with rotating means, a dynamic vibration damping device including a pendulum which comprises, in combination, a supporting part, a pendular mass, at least two corresponding surfaces one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation, said links being elastically secured to at least one of the two parts to which they are secured at their ends so as to produce an increase of the pendular radius in response to an increase of the centrifugal force, and means for reducing friction between each link and the corresponding surface of the supporting part upon sliding of one on the other.

21. In combination with rotating means, a dynamic vibration damping device including a pendulum which comprises, in combination, a supporting part, a pendular mass, at least two corresponding surfaces, one rigid with said supporting part and the other rigid with said pendular mass, and two flexible links each secured at one end to said supporting part and at the other end to said pendular mass so as each to pass around said two surfaces and to wind on one while simultaneously unwinding from the other during pendular oscillation, said links being adapted to produce increase of the pendular radius when the centrifugal force increases, means for limiting the increase in the pendular radius to stages, said means being actuated to permit an increase from one stage to the next only when the centrifugal force of said pendular mass has reached predetermined amounts.
